UNITED STATES PATENT OFFICE.

CLARK TAMMADGE, OF COLUMBUS, OHIO.

DESIGN FOR A FINGER-RING.

49,680.

Specification for Design. Patented Sept. 19, 1916.

Application filed April 25, 1916. Serial No. 93,566. Term of patent 7 years.

● *To all whom it may concern:*

Be it known that I, CLARK TAMMADGE, a citizen of the United States, residing at Columbus, in the county of Franklin and State of Ohio, have invented a new, original, and ornamental Design for Emblematic Base-Ball Finger-Rings, of which the following is a specification, reference being had to the accompanying drawing, forming part thereof.

The Figure 1. showing full edge view,

Fig. 2. showing top view of ring, Fig. 3. showing side view of emblematic base ball finger ring, showing my new design.

I claim:

The ornamental design for a finger ring, as shown.

CLARK TAMMADGE.

Witnesses:

ARTHUR S. BURKET,
ELIZABETH TAMMADGE.
